WEATHER STRIP GROOVE ADJUSTER AND
SASH RETAINER

Joseph P. Glaser and Leon E. Willett, Detroit,
Mich., assignors to Chamberlin Metal Weather
Strip Company, Detroit, Mich., a corporation
of Michigan

Application April 23, 1940, Serial No. 331,198

15 Claims. (Cl. 292—70)

This invention relates to window weatherstrip structures and in particular to a device for increasing the efficiency of such structures.

One object of the invention is to provide a weatherstrip groove adjuster and sash retainer which will tighten the engagement of the sash with the weatherstrip and also apply a force to the weatherstrip to frictionally hold the sash in any desired position of adjustment.

Another object is to provide a weatherstrip groove adjuster and sash retainer wherein an elongated element is urged laterally into frictional engagement with the weatherstrip so that it reduces the channels otherwise available for the entry of outside air and at the same time frictionally engages the weatherstrip so that the sash will remain partially or wholly open or closed without the necessity for providing sash weights or springs.

Another object is to provide a weatherstrip groove adjuster and sash retainer wherein the sash is provided with a longitudinal groove containing a laterally expansible bar engaging the weatherstrip and closing up any cracks existing therebetween.

Another object is to provide a device as set forth in the preceding object wherein the bar is urged wholly laterally into engagement with the weatherstrip, yet is prevented from engaging the window frame with any appreciable force.

Another object is to provide a device as set forth in the preceding objects wherein a split bar is spread apart by a wedge device actuated by means projecting through the sash and adjustable without removing the window stop or other window or sash structure.

Another object is to provide a device as set forth in the preceding objects wherein a lever is provided for urging the bar laterally against the weatherstrip rather than outwardly against the window frame.

In the drawings:

Figure 1 is a side elevation, partly in section, of a window assembly equipped with a preferred embodiment of the weatherstrip groove adjuster and sash retainer of the present invention.

Figure 2 is a horizontal section taken along the line 2—2 of Figure 1.

Figure 3 is a vertical section taken along the line 3—3 in Figure 1.

Figure 4 is an enlarged horizontal section taken along the line 4—4 through the axis of the wedging screw.

Figure 5 is a perspective view of the expansible

bar shown in Figures 1 to 4, inclusive, and removed from the window assembly.

Figure 6 is a horizontal section similar to Figure 2, but showing a modification wherein the bar is urged transversely by a lever and screw.

Figure 7 is a side elevation, partly broken away and in section, of the modification shown in Figure 6.

Figure 8 is a perspective view of a portion of the bar removed from the modifications of Figures 6 and 7.

Figure 9 is a horizontal section similar to Figure 2 of a modification employing an expanding wedge with a screw cam expander.

Figure 10 is a side elevation partly broken away and in section, of the modification shown in Figure 9.

Figure 11 is a transverse section taken along the line 11—11 in Figure 9, but showing only the sash and the portion of the window strip engaged by the expansible bar.

General arrangement

In general, the weatherstrip groove adjuster and sash retainer of this invention consists of a bar mounted in a longitudinal groove in the edge of the sash, together with various means for urging a portion of the bar transversely of the sash into engagement with the portion of the weatherstrip entering the sash groove. The force is preferably applied wholly transversely so that the bar is not urged outwardly into engagement with the window frame. In the principal form of the invention the bar has longitudinal slots provided with screw-actuated wedges for expanding it transversely into engagement with the weatherstrip.

In one modification, the bar is urged transversely by a lever which in turn is actuated by a screw. In another modification a slotted bar is expanded transversely by a wedge engaged by a screw perpendicular to the axis of the wedge and having a cam action thereon.

Hitherto the building art has often employed prefabricated window frame and sash units which are manufactured at the factory and later installed in the building. Manufacturers of these units have been unable to determine the exact fit which the sash should have with the window frame in view of the fact that the unit is afterward exposed to moisture which expands the parts if, as usual, they are made of wood.

In particular, a window and sash unit installed in a newly erected building is usually mounted adjacent freshly plastered walls. This plaster

contains a large amount of water which slowly escapes as the plaster hardens. Much of the water enters the wooden window frame and sash, causing them to expand and bind. The sash and window frame are preferably made so that they will have a relatively snug fit when dry, because only by such a snug fit can the entrance of air around the edge of the sash be prevented. If, however, such a snugly fitting unit is mounted in a freshly plastered building, the consequent expansion of the wooden frame and sash causes them to bind and renders the window incapable of being opened or closed. In order to prevent this binding, therefore, it has been necessary hitherto to leave large clearance spaces between the sash and the adjacent window frame. These large clearances enable the sash and window frame to expand considerably as they become impregnated with the moisture from the plaster walls, so that a fairly snug fit is obtained when the parts are damp. When the parts dry out, however, large cracks are frequently left between the sash and the window frame through which wind will blow, causing drafts and cooling of the house.

The present invention eliminates these difficulties by providing a transversely urged bar engageable with the portion of the weatherstrip entering the sash groove. Since this bar is urged only in a substantially transverse direction, it does not expand outwardly into engagement with the window frame. As the bar tightly engages the weatherstrip, no cracks remain through which wind can enter. At the same time, the bar engages the weatherstrip with a sufficient frictional effect to hold the window fully or partially open at any desired point, thereby eliminating the need for sash counterweights or springs.

Preferred construction

Referring to the drawings in detail, Figure 1 shows a window and sash unit having a sash 10 with upper and lower stiles 11 and 12 and side stiles 13. The side stiles 13 move up and down in a space formed by the window frame members 14 and side members 15 and 16. The side member 16, or parting stop, is mounted in a groove 17 in the window frame 14. The sash stiles 11, 12 and 13 are provided with the usual recess 18 for receiving the window pane 19, the latter being held in position by the usual putty or other retaining portion 20.

The interior of the window frame 14 is provided with a weatherstrip 21 (Figure 2) having a base portion 22 and a tongue 23 projecting into a groove 24 within the sash side stiles 13. Mounted in the groove 24 is a groove adjusting member 25 consisting of an elongated bar with its outer edge substantially flush with the side edge of the stile 13 of the sash 10.

Various means are provided for urging the bar 25 transversely of the sash 10 into engagement with the weatherstrip tongue 23 and since the adjusting member 25 is substantially flush with the side of the stile 13 it will be engageable with the weatherstrip portion 21. In the principal embodiment (Figures 1 to 5) the bar 25 is provided with elongated slots 26 having wedge shaped portions 27 engaged by wedges 28. The wedges 28 are provided with threaded bores 29 engaged by the threaded ends 30 of expanding screws 31 having enlarged shanks 32. Disposed between the bar 25 and the shoulder 33 formed by the portions 31 and 32 is an abutment member 34 (Figure 4). The shank 32 of each ex-

panding screw 31 is provided with the usual screw driver slot 35 at the outer end thereof.

Operation

5 In the operation of the preferred form of the invention (Figures 1 to 5 inclusive), the bar assembly, generally designated 36 (Figure 5) is inserted in the sash groove 24 with the screw shanks 32 pushed outwardly through the holes 37 provided in the sash stiles 13. The sash assembly is then placed in position in the usual manner with the tongue 23 entering the groove 24 and engaged transversely by the bar 25. The parting stops 16 are then placed in position in the known manner.

10 In order to take up any excessive clearances between the bar 25 and the weatherstrip tongue 23, a screw driver is inserted in the slots 35 of the shanks 32 and rotated. This causes the wedge 28 to enter the slot portion 27, expanding the bar 25 transversely as shown in Figure 3. The abutment member 34 prevents the bar 25 from moving further into the groove 24 while this is occurring.

15 As a consequence, the expansion of the bar 25 transversely effects a frictional engagement with the weatherstrip tongue 23 and at the same time brings about a frictional contact therewith. This action has the double result of closing up any excessive clearances and at the same time producing a frictional drag which counteracts the weight of the window sash 10 and holds the latter open either partially or wholly, in any desired position.

20 From time to time the engagement of the bar 25 with the weatherstrip tongue 23 may be adjusted to the desired degree merely by turning the screws 31. If a high humidity, such as during the summertime, causes the bar to engage 30 the weatherstrip too tightly, the screw 31 may be rotated in a counterclockwise direction, causing the wedge 28 to move outward relatively to the wedge slot 27, thereby permitting the bar 25 to contract transversely.

Modified lever construction

25 The modified lever construction of Figures 6 and 7 employs similar principal elements to the preferred embodiment shown in Figures 1 to 5, inclusive, these elements being similarly numbered. The bar 25, however, in this modification, is solid and is provided with recesses 40 engaged by the bent ends 41 of spring levers 42 and it is noted that the adjuster element 25 has 30 its outer edge substantially flush with the edge of the stile 13. The latter are mounted in recesses 43 in the sash stiles 13 and are engaged by screws 44 passing through holes 45 in the levers 42.

35 In the operation of the modification shown in Figures 6 and 7, the bar 25 is urged transversely by tightening the screws 44. This causes the ends 41 of the lever 42 to move in a transverse direction, urging the bar 25 against the weatherstrip tongue 23. The screws 44 may be tightened or loosened to vary the pressure with which the bar 25 engages the weatherstrip tongue 23, thereby adapting the device to the proper adjustment required by different conditions of humidity or climate. At the same time, the frictional engagement between the bar 25 and the weatherstrip tongue 23 can be varied so as to vary the force which the user must apply in order to close or open the window.

40 As in the case of the preferred embodiment,

te modification of Figure 6 also enables the elimination of sash counterweights or springs since the window is held wholly or partially open in any desired position by the frictional engagement between the bar 25 and the weatherstrip tongue 23.

Modified cam construction

The modified cam construction of Figures 9, 10 and 11 employs similar principal elements to the preferred embodiment shown in Figures 1 to 8, inclusive, these elements being similarly numbered. The wedges 28, however, in this embodiment are provided with stems 50 having conical transverse holes 51 near the ends thereof remote from the wedges 28. The sash groove 24 is provided with extension recesses 52 containing blocks 53 having mutually perpendicular bores 54 and 55 for the reception of the stems 50 and adjusting screws 56 respectively. The bores 55 are, of course, threaded to receive the corresponding threads of the adjusting screws 56 and the latter are provided with conical heads 57 (Figure 9) for engaging the walls of the conical holes 51. The sash stiles 13 are provided with transverse bores 58 aligned with the threaded bores 55 through which the screws 56 enter the latter.

In the operation of the modification shown in Figure 9, the device is assembled in a similar manner to the preferred embodiment of Figure 2, with the wedges 28 within the wedge slots 27. To expand the bar 25 laterally, the screws 56 are rotated clockwise so that their conical ends 57 enter and engage the walls of the conical holes 51. This provides a cam action urging the wedges 28 into the wedge grooves or slots 27, expanding the bar 25 transversely into engagement with the weatherstrip tongue 23. In this modification, as in Figure 2, the opposite side of the bar 25 engages the opposite side of the groove 24 as an abutment.

Thus, in the modification of Figure 9, the bar 25 is urged into frictional engagement with the weatherstrip tongue 23 and at the same time any excessive clearance therebetween is closed up to the desired amount. In this way, as in the previously described embodiments, the bar assembly 36 not only eliminates the need for sash counterweights or springs, but also increases the efficiency of the weatherstrip structure by providing an adjustment thereof.

In the modification, as in Figures 1 to 5, the outer edge of the adjuster member 25 extends substantially flush with the outer edge of the groove in the vertical stile 13 so as to cause the same to be engageable with the weatherstrip 21 when the same is slightly expanded from atmospheric conditions to thereby create a snug fit and exclude as much air as possible.

While a specific embodiment of the invention has been described and illustrated, it will be understood that various modifications may be made within the scope of the appended claims without departing from the spirit of the invention.

What we claim is:

1. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess, and means for urging said adjuster transversely into engagement with said weatherstrip portion in a direc-

tion transverse to the window pane having its outer edge substantially flush with the outer edges of the longitudinal recess engageable with another portion of said weatherstrip.

- 5 2. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess, and means for urging said adjuster into engagement with said weatherstrip portion in a direction transverse to the window pane and having its outer edge substantially flush with the outer edges of the longitudinal recess engageable with another portion of said weatherstrip to said groove.
- 10 3. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess, and means for urging said adjuster into engagement with said weatherstrip portion in a direction transverse to the window pane and to said groove, said adjuster being elongated and substantially parallel with said window frame structure having its outer edge substantially flush with the outer edges of the longitudinal recess engageable with another portion of said weatherstrip.
- 15 4. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess, and means for urging said adjuster into engagement with said weatherstrip portion in a direction substantially perpendicular to the window pane and to said weatherstrip portion having its outer edge substantially flush with the outer edges of the longitudinal recess engageable with another portion of said weatherstrip.
- 20 5. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess, and resilient means for urging said adjuster transversely into engagement with said weatherstrip portion in a direction transverse to the window pane.
- 25 6. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess and having a longitudinal depression therein, and force exerting means in said depression for laterally moving a portion of said adjuster transversely into engagement with said weatherstrip portion in a direction transverse to the window pane having its outer edge substantially flush with the outer

edges of the longitudinal recess engageable with another portion of said weatherstrip.

7. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess and having a longitudinal cavity therein, a wedge device in said cavity, and means for urging said wedge device into said cavity for moving a portion of said adjuster transversely into engagement with said weatherstrip portion in a direction transverse to the window pane.

8. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess and having a longitudinal cavity therein, a wedge device in said cavity, and screw actuated mechanism for urging said wedge device into said cavity for moving a portion of said adjuster into engagement with said weatherstrip portion in a direction transverse to the window pane.

9. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess and having a longitudinal cavity therein, a wedge device in said cavity, an abutment engaging said adjuster beyond said cavity, and screw actuated mechanism for urging said wedge device toward said abutment for moving a portion of said adjuster transversely into engagement with said weatherstrip portion in a direction transverse to the window pane.

10. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess and having a longitudinal cavity therein, a wedge device in said cavity, and cam means engaging said wedge device for urging said wedge device into said cavity for moving a portion of said adjuster transversely into engagement with said weatherstrip portion in a direction transverse to the window pane.

11. In a sash retainer adapted to be received in a longitudinal recess and adjustably press against and move longitudinally with respect to a weatherstrip extending into said recess, thereby adjusting the friction between the moving parts of a weatherstripped sliding sash and window

frame structure, the combination of an adjuster element mounted in said recess and having a longitudinal cavity therein, a wedge device in said cavity having a cam contact surface and a cam engageable with said cam contact surface for moving a portion of said adjuster transversely into engagement with said weatherstrip portion in a direction transverse to the window pane.

12. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess, a laterally movable element engageable with said adjuster, and means for moving said element toward said adjuster for urging said adjuster transversely into engagement with said weatherstrip portion in a direction transverse to the window pane.

13. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess, a laterally movable lever element engageable with said adjuster, and means for actuating said lever element for moving a portion of said adjuster transversely into engagement with said weatherstrip portion in a direction transverse to the window pane.

14. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an adjuster element mounted in said recess, a laterally movable lever element engageable with said adjuster, and means for moving said element toward said adjuster for urging said adjuster transversely into engagement with said weatherstrip portion in a direction transverse to the window pane, said lever element having a resilient part yieldingly engaging said adjuster.

15. In a sash retainer adapted to be received in a longitudinal recess and adjustably press against and move longitudinally with respect to a weatherstrip extending into said recess, thereby adjusting the friction between the moving parts of a weatherstripped sliding sash and window frame structure, the combination of an elongated adjusting member mounted in said recess and having a longitudinal cavity therein, an elongated wedge in said cavity, an abutment on the opposite side of said member from said wedge, and means for urging said wedge into said cavity toward said abutment whereby to move a part of said adjusting member transversely into engagement with said weatherstrip portion in a direction transverse to the window pane.

JOSEPH P. GLASER.
